(57) **CLAIM**

The ornamental design for a combined water spout and waste outlet as shown and described.

DESCRIPTION

1. Combined water spout and waste outlet

Figure 1.1 is a perspective view of a combined waterspout and waste outlet according to the invention;

Figure 1.2 is a second perspective view thereof;

Figure 1.3 is a third perspective view thereof.

The broken lines in the reproduction depict portions of the combined water spout and waste outlet which form no part of the claimed design. The broken lines showing the rectangular plane depict environmental structure of the combined water spout and waste outlet and form no part of the claimed design.

1 Claim, 3 Drawing Sheets
